UNITED STATES PATENT OFFICE.

FRANK KORNER, OF GALESBURG, ILLINOIS, ASSIGNOR TO WINSLOW BOILER & ENGINEERING COMPANY, OF CHICAGO, ILLINOIS, A CORPORATION OF ILLINOIS.

LIQUID-FUEL BURNER.

Application filed February 11, 1921, Serial No. 444,094. Renewed March 10, 1924.

To all whom it may concern:

Be it known that I, FRANK KORNER, a citizen of the United States, residing at Galesburg, in the county of Knox and State of Illinois, have invented certain new and useful Improvements in Liquid-Fuel Burners, of which the following is a specification, reference being had therein to the accompanying drawing.

10 The invention relates to liquid fuel burners, and consists in the matters hereinafter described and then pointed out in the claims.

15 In the accompanying drawing, which illustrates a practical embodiment of my invention, Fig. 1 is a plan view of the device with part of the top flange of the pot broken away for convenience of illustration;

20 Fig. 2 is a view in side elevation with the pot in vertical section on the line 2—2 of Fig. 1, and

Fig. 3 is a view of the pot in transverse vertical section on the line 3—3 of Fig. 1.

25 In the drawing the reference numeral 10 indicates an air-duct connected at its intake end to an air-blower 11 of a type capable of delivering a sufficient quantity of air to ensure perfect combustion, and with its outlet end connected tangentially with the fire-pot 12 which is provided with a suitable opening for this purpose. By this arrangement the air for supporting the combustion of the flame in the burner is delivered to the fire-pot in a tangential stream.

30 The fire-pot or combustion chamber 12 is of any suitable contour in plan section to conform to the design of the steam generator or boiler with which it is associated, and in the present instance it is substantially circular. Its bottom plate 13 is flat, and its 35 walls 14 are vertical, being curved at their upper and lower portions to form a rounded connection with the bottom 13 and an inwardly projecting ledge 15 forming the flame-discharge opening at the top and which is more or less restricted and smaller in diameter than the cross-sectional area of the interior. The chamber 12 is provided 40 interiorly with baffle or deflector plates 16, preferably arranged in a pair spaced apart on the wall opposite to the air-inlet opening. Each plate 16 is secured to the inner wall of the chamber and extends approximately the 45 height of the chamber and is spirally inclined from its top to bottom rearwardly or 50 in the general direction of the travel of the

55 air current introduced through the tangential air inlet, and also is rounded or curved in cross-section so that its free edge extends forwardly in advance of its other edge toward the air-inlet or in the direction opposite to the direction of travel of the air current as it passes around the pot.

60 The fuel oil is introduced through a nozzle 17 arranged on the leeward side of the air inlet, and falls upon a distributing plate 18 which is located near the bottom of the pot and by which it is broken up and splashed into the chamber. This plate is inclined from its rear toward the center of the chamber to throw the oil particles forward as well as laterally, and not only atomizes the oil falling upon it but also deflects and spreads the igniting flame of a pilot burner 19 which is located beneath it; and the plate is preferably provided with 65 perforations which allow the oil to drip through and further atomize it in contact with the flame. By this arrangement the burner 19 ignites the fuel and starts the heating flame in the pot, which continues to burn as long as the oil is supplied to it. The bottom 13 is provided with a drain opening 20 normally closed by a plug to draw off any oil that may escape into the 70 pot while the device is out of operation.

75 As the baffle-plates are arranged with their upper-ends in advance or toward the air-inlet they lead downwardly to divert the inflowing supply of air downwardly toward the floor of the chamber and into the zone where the oil is broken up and splashed into the chamber by the distributing-plate, and the concavity of the baffle-plates being 80 on their windward side or toward the air-inlet they present their concave faces to the inflowing air and turn the swirling or rotating currents back on themselves and toward the center of the chamber to fill its entire area with the fuel mixture and direct the currents into the central flame-discharge 85 opening at the top of the chamber.

90 When the fuel oil enters the pot it is atomized more or less by the distributing plate 18 and is readily ignited by the pilot flame, it being understood that the blower 95 is then operating to furnish the air necessary to ensure complete combustion of the oil. The air passes into the pot in a tangential column, and mixes with and further atomizes the oil to form the combustible 100

mixture, which assumes a gyrating or swirl-
ing course around the pot, and the baffle or oil distributing plate near the bottom of
deflector plates direct the moving body of the fuel mixture toward the central discharge
opening where it forms a central column of flame of great intensity which fills and pro-
jects out of the opening.

I claim:

1. In a liquid fuel burner, a chamber hav-
ing a tangential air-inlet, an oil supply, an
oil distributing plate near the bottom of the
chamber, and baffle plates arranged in a
spaced pair opposite the air inlet and lead-
ing downwardly to deflect the fuel mixture
toward the center of the chamber.

2. In a liquid fuel burner, a chamber hav-

ing a tangential air-inlet, an oil supply, an
oil distributing plate near the bottom of
the chamber, and baffle plates arranged op-
posite the air inlet and inclined from top to
bottom in the direction of the movement of
the air current and curved in cross-section
toward the air-inlet.

3. In a liquid fuel burner, a chamber hav-
ing a tangential air-inlet, an oil supply, a 25
perforated oil distributing plate at the bot-
tom of the chamber, an igniting device
under the plate, and baffle plates constructed
to deflect the air toward the distributing
plate and the fuel mixture toward the center 30
of the chamber.

FRANK KORNER.
